UNITED STATES PATENT OFFICE

SAMUEL BALIN, OF NEW YORK, N. Y., ASSIGNOR TO UNITED AUTO TRUNK CO., OF NEW YORK, N. Y., A CORPORATION OF NEW YORK

WARDROBE HATBOX

Application filed April 20, 1928. Serial No. 271,500.

This invention relates to hand carried luggage with special reference to such as are used by women in travelling for the convenient and safe transportation of hats, 5 wearing apparel, toilet articles and like impediment, not readily carried in a conventional suit case.

It is one of the objects of the present invention to provide a container designed 10 specifically for the purpose of carrying such articles and in such manner as to avoid injury to the same even when subjected to the hazards of rough handling during travel.

A further feature is in the provision of a 15 series of clothes hangers arranged within the container and having means whereby garments draped thereon are held closely against the inner surface of the box cover, elastically restrained along their length and their lower 20 ends held in a compartment in the main portion of the box adjacent a hat compartment.

Another aim is to produce means whereby any of the hangers may be removed without disturbing the others.

25 These and other important features which will become apparent as the description progresses, are attained by the novel design, construction, and arrangement of parts herein-after described and shown in the accompanying drawing, constituting a material part of this disclosure, and in which:-

Figure 1 is a perspective view of an embodiment of the invention shown in an open position.

35 Figure 2 is a front elevational view of one of the hangers as supported in the cover.

Figure 3 is a front view of one of the hanger support brackets.

40 Figure 4 is a similar view of the mating bracket.

Figure 5 is a transverse sectional view taken on line 5—5 of Figure 3.

Figure 6 is an end view of the bracket shown in Figure 3.

45 Figure 7 is a plan view showing the method of fastening one of the hanger pintles.

A sturdy rectangular case is shown in the drawing, consisting of two main portions, which may be considered respectively body 10 50 and cover 11 connected by hinges at the rear

and provided with the usual latching or locking devices.

The body is shaped to present its side walls as inclined downwardly from the rear to the front and the cover is complementary, both 55 being provided with a carrying handle 12.

A transverse partition 13 in the body forms a front compartment 14, substantially square in cross section and adapted to provide ample space for one or more hats without damage 60 to their brims, the interior walls being provided with cushion linings 15 behind which small articles may be disposed.

Rearward of the compartment 14 is a relatively narrow chamber 16 extending from one 65 side to the other of the receptacle in its deeper portion and into which garments supported by the cover may extend.

Secured on one of the inner sides of the cover 11, at its deeper front portion is a 70 bracket 17 provided with a series of openings 18—18—18" and on the opposite side is a similar bracket 19 having a slot 20, open at the front end of the bracket and from 75 which are formed spaced, downreaching recesses 21—21—21" leading to undercut passages 22—22—22" extending towards the front and terminating in upreaching niches 23—23'—23".

Disposed in the bracket 19 is a thin flat bar 80 24, guided at its ends by slots 25 in the bracket end walls and pressed normally upward to the limit of the slots, to a position just above the niches 23 by a bowed flat spring 26.

The clothes hangers 28 are of conventional 85 pattern arranged to support flexible articles on a bar 29, as entered through an opening in the hanger, and also to receive goods disposed over the top bar, these hangers extending substantially the full length of the container cover.

At the ends of the upper bar 29' are secured 90 clevises 30 having central extensions 31 and set in these extensions are the stems of rectangular pintles 32, either of which are engageable in the openings 18 or enterable in the slot 20 to pass selectively into the recesses 21 and, upon depressing the bar 24, move towards the front in the passages 95 22 to eventually enter the niches 23 being 100

pressed upward therein by the spring supported bar 24.

As the pintles are square in cross section, as are also the openings and passages in the brackets, it will be obvious that the hangers 5 28 may be reversed and in whatever position they may be entered in the brackets they will be prevented from swinging being held parallel at all times with the outer wall of the cover.

10 In addition the articles suspended on the hangers are further held against the inner surface of the cover by means of elastic straps 33 one or more of which may be used, these straps being fastened at one end to the inner 15 side of the cover and connected by catches 34 to the opposite side, permitting the articles, if of considerable length to enter the chamber 16.

From the foregoing it will be seen that a 20 number of articles of personal wear may be safely and surely retained in good condition while travelling, and that several robes may be readily disposed upon the hangers in such manner as to retain their shape and neatness 25 of appearance until required for use.

Although I have described my improvement with considerable detail and with respect to a particular form of my invention, I do not desire to be limited to such detail 30 since many changes and modifications may well be made without departing from the spirit and scope of my invention in its broad-est aspect.

Having thus described the invention, what 35 is claimed as new and desired to secure by Letters Patent, is:—

1. A traveller's case comprising a rectangular container having a body and cover portion hingedly united, each being provided 40 with handles at the front, the side edges of said body and cover being inclined upwardly from the front to the rear, a transverse partition in said body forming a main forward compartment and a narrow rear compartment, brackets fixed to the inner side walls of said cover at its deeper front portion one of said brackets having rectangular openings and a slot having downreaching recesses in the other bracket, the recesses terminating in raised niches at their forward ends, clothes hangers having square pintles 45 at their ends to enter the openings in the first named bracket, their opposite ends adapted to pass into the slot in the other bracket to 50 eventually engage in the niches, resilient means to retain the pintles entered in the niches, and elastic straps in said cover to confine articles on said hangers against the inner surface of said cover, the lower ends of 55 said articles entering the narrow compartment in said body.

2. In a traveller's case having a body and cover foldable thereover, a pair of sheet metal brackets fixed in the ends of said cover, one 60 of said brackets having a series of rectangu-

lar openings and the other containing an elongated slot communicating with upstanding square niches, reversible hangers having square pintles on their ends to engage in the bracket openings at one end and to move in the slot of the opposite bracket to selectively engage the niches therein, and a spring supported bar to normally press the hanger pintles into the niches whereby the hangers are maintained parallel with the outer wall of 75 said cover.

This specification signed this fifth day of April, 1928.

SAMUEL BALIN.
